AEROPLANE

Henrik Anather-Henrikson, West Englewood, N. J.

Application June 5, 1934, Serial No. 729,083

9 Claims. (Cl. 244—23)

The present invention relates to aeroplanes and embodies, more specifically, an improved aeroplane construction by means of which the hovering ability of the plane may be greatly increased over existing types of constructions. More particularly, the invention embodies mechanism by means of which vertical movements of the plane may be greatly facilitated.

Heretofore mechanism has been provided by means of which the hovering and vertical movement of planes may be facilitated, this existing form of mechanism embodying mechanical devices such as propellers lying in horizontal planes, etc., and the functioning of these mechanisms not only is less effective than if designed for a plane which is not designed primarily for horizontal travel but the resulting structure is frequently such as to add great weight to the plane and seriously impair its speed of travel in horizontal directions. Moreover, such existing mechanisms are rather inefficient in operation.

An object of the invention, accordingly, is to provide a means by which an aeroplane of the usual form, designed for fast horizontal travel may be manoeuvred vertically with facility.

A further object of the invention is to provide in combination with the usual aeroplane mechanism for horizontal travel a means for manoeuvring the plane vertically, the means employing portions of the plane which are necessary for horizontal travel.

A further object of the invention is to provide a device of the above character wherein the means for facilitating vertical movement of the plane is comparatively inexpensive and of little weight and does not impair the efficiency of the plane.

A further object of the invention is to provide mechanism of the above character wherein means is incorporated for utilizing the usual wings of the aeroplane as a barrier upon opposite sides of which regions of high and low pressure may be created to facilitate the hovering and vertical manoeuvres of the plane.

A further object of the invention is to provide a device of the above character wherein means is provided for discharging the exhaust gases of the plane through the wing areas to effect heating of the wings and thus preventing an accumulation of ice and snow.

A further object of the invention is to provide in combination with a means of the above character, a structure such as to create vortices above and below the wing structure of a plane to increase the vertical manoeuvring ability thereof.

Further objects, not specifically enumerated above, will be apparent as the invention is described in greater detail in connection with the accompanying drawings, wherein:

Figure 1 is a plan view partly broken away and in section showing an aeroplane constructed in accordance with the present invention.

Figure 2 is a view in section, taken on line 2—2 of Figure 1, and looking in the direction of the arrows.

Figure 3 is a view in section, taken on line 3—3 of Figure 1, and looking in the direction of the arrows.

Figure 4 is a detail plan view showing the fan mechanism of Figure 3.

Figure 5 is an enlarged detail view of a wing of an aeroplane constructed in accordance with the present invention, showing a modified form thereof, this view showing the apertures in the suction side of the wing.

Figure 6 is a view similar to Figure 5, showing the fan mechanism, the apertures shown being those in the underside of the wing through which air is discharged under pressure.

Figure 7 is a view in section, taken on line 7—7 of Figure 6, and looking in the direction of the arrows.

Figure 8 is a view in section, taken on line 8—8 of Figure 5, and looking in the direction of the arrows.

Figure 9 is a plan view showing the hull and tail structure of an aeroplane constructed in accordance with the present invention, provided with means by which ice and snow may be prevented from accumulating on the ailerons and associated structure.

Figure 10 is a view in section, taken on line 10—10 of Figure 9, and looking in the direction of the arrows.

Figure 11 is a view in section, taken on line 11—11 of Figure 9, and looking in the direction of the arrows.

Figure 12 is a segmental view showing the form of one of the apertures shown in Figures 5 and 6.

Figure 13 is a view in section, taken on line 13—13 of Figure 12, and looking in the direction of the arrows.

The present invention is a continuation in part of applicant's copending application Ser. No. 705,089, filed January 3, 1934, and incorporates certain additional features which will be described hereinafter.

In the construction shown in Figures 1 through 4, 1 indicates the hull of an aeroplane provided with wings 2 upon the opposite sides thereof. The

upper surfaces of wings 2 are formed with apertures 3 which communicate with ducts 4, extending longitudinally of the wings. The ducts 4 are formed by angularly disposed partition members 5 3' and communicating with the suction chambers 5 of impellers 6 located in the fuselage of the plane.

The impellers 6 may be driven from a power shaft through suitable gear connections 7 and 10 are provided with pressure or discharge chambers 9 which communicate with pressure ducts 10 formed between the partition members 3' and communicating with apertures 11, formed in the undersides of the wings 2. Control valves or 15 dampers 12 may be provided to facilitate the control of the flow of air through the respective ducts and, in operation, the fans or impellers 6 are driven to draw air in through the apertures 3 and create a suction of the upper sides of the 20 wings 2, the air being discharged through the apertures 11 to create a region of relatively high pressure beneath the wings, thus exerting an appreciable lifting force thereon.

In the construction shown in Figures 5 through 25 8, certain of the openings 13 in the upper surface of the wings 2 are positioned in such fashion as to form an Archimedean spiral around the center of gravity 14 of the respective wings. On one side of a longitudinal line passing through 30 the center of gravity of the wing, inlet ports or openings 15 are formed all extending in one direction. On the other side of this longitudinal line openings or ports 16 are formed, all extending in a common direction. The direction or planes 35 in which the openings 15 and 16 lie intersect approximately in the longitudinal line above referred to and form acute angles which, with the longitudinal line, form a plurality of Y's, as viewed from the fuselage of the machine. As a 40 result, the flow of air into the wing is such as to form a vortex about the center of gravity of the wing and thus, by reason of the whirling motion of the air, the suction created is substantially increased.

45 On the underside of the wing, as viewed in Figure 7, openings 17 and 18 are formed in the wing on the outer end thereof with respect to the center of gravity of the wing. On the underside of the center of gravity of the wing, openings 19 and 50 20 are formed, these openings lying in planes which form acute angles with a longitudinal line passing through the center of gravity of the wing, the planes in which the openings 19 and 20 lie, together with the longitudinal center line of 55 the wing forming Y's, as viewed from the end of the wing. About the center of gravity 14 of the wings are formed openings 21 which are arranged in the form of an Archimedean spiral and thus cause air to be directed from the wing with a 60 whirling motion. The direction and manner in which air is directed from the openings 17, 18, 19 and 20 is such as to cause the air streams from the openings to converge in the region of the spiral. By creating a vortex or whirling column 65 of air directed downwardly from the wing below the center of gravity thereof and by causing the confluence of the aforementioned air streams to coincide with this whirling column, the pressure effect created beneath the wing is greatly increased.

70 As shown in Figures 12 and 13, the inner sides of the wings are formed with deflectors 22 which direct the air streams through the respective openings in a desired manner. Obviously, the 75 form and arrangement of these openings should

follow the best engineering practice in order to utilize the full efficiency of the air flow upon opposite sides of the wings and the particular arrangement shown in the drawings is not necessarily illustrative of the most effective arrangement. 5

In order that the accumulation of ice and snow on the wings may be avoided, the exhaust from the engine is directed from the exhaust pipe through an extension pipe line 23 and discharged through outlet 24 which directs the exhaust through the discharge ducts 10. In this fashion, 10 the surfaces of the wings are heated and any such accumulation prevented or destroyed.

In the construction shown in Figures 9, 10, and 15 11, discharge ducts 25 communicate with the pressure side of the impellers 6 and direct air rearwardly into outlet manifolds 26 which are formed with nozzles 27 which direct the air rearwardly over the control fins 28. In this fashion, 20 20 the control fins may be turned upon their horizontal axes and the air is directed upon either side thereof to facilitate the control of the machine.

While the invention has been described with specific reference to the accompanying drawings, 25 it is not to be limited, save as defined in the appended claims.

I claim as my invention:

1. An aeroplane having means forming an air deflecting surface for normal travel, and ducts 30 and apertures formed in the said means, the apertures and ducts being spirally oriented to create a region above the surface of rarefied air having a whirling motion.

2. An aeroplane having means forming an air deflecting surface for normal travel, and ducts 35 and apertures formed in the said means, the apertures and ducts being spirally oriented to create a region above the surface of rarefied air having a whirling motion, about an axis passing 40 through the center of gravity of the surface.

3. An aeroplane having means forming an air deflecting surface for normal travel, spirally oriented ducts and apertures formed in the upper 45 surface of said means to create a region above the surface of rarefied air having a whirling motion, and spirally oriented ducts and apertures formed in the upper surface of said means to create flow of air above and toward the surface at angles to a line perpendicular to the normal 50 direction of travel.

4. An aeroplane having means forming an air deflecting surface for normal travel, spirally oriented ducts and apertures formed in the upper surface of said means to create a region above 55 the surface of rarefied air having a whirling motion about an axis passing through the center of gravity of the surface, and spirally oriented ducts and apertures formed in the upper surface of said means to create flow of air above and toward the surface at angles to a line perpendicular to the normal 60 direction of travel and passing through the center of gravity of the surface.

5. An aeroplane having means forming an air deflecting surface for normal travel, and ducts 65 and apertures formed in the said means, the apertures and ducts being spirally oriented to create an air pressure region below the surface having a whirling motion.

6. An aeroplane having means forming an air deflecting surface for normal travel, and ducts 70 and apertures formed in the said means, the apertures and ducts being spirally oriented to create an air pressure region below the surface 75

having a whirling motion about an axis passing through the center of gravity of the surface.

7. An aeroplane having means forming an air deflecting surface for normal travel, spirally oriented ducts and apertures formed in the upper surface of said means to create an air pressure region below the surface having a whirling motion, and spirally oriented ducts and apertures formed in the upper surface of said means to 10 create flow of air beneath and away from the surface in a plurality of converging paths.

8. An aeroplane having means forming an air deflecting surface for normal travel, spirally oriented ducts and apertures formed in the upper 15 surface of said means to create an air pressure region below the surface having a whirling motion, and spirally oriented ducts and apertures

formed in the upper surface of said means to create a flow of air beneath and away from the surface in a plurality of paths converging about the axis of the whirling air.

9. An aeroplane having means forming an air 5 deflecting surface for normal travel, spirally oriented ducts and apertures formed in the upper surface of said means to create an air pressure region below the surface having a whirling motion, and spirally oriented ducts and apertures 10 formed in the upper surface of said means to create flow of air beneath and away from the surface in a plurality of converging paths on each side of a line perpendicular to the direction of travel of the aeroplane and passing through 15 the axis of the whirling air.

HENRIK ANATHOR-HENRIKSON.
